UNITED STATES PATENT OFFICE.

LEE H. ADAMSON, OF ROGERS, ARKANSAS.

EXTENSIBLE HOLDER.

1,203,562.

Specification of Letters Patent.

Patented Nov. 7, 1916.

Application filed December 13, 1915. Serial No. 66,565.

To all whom it may concern:

Be it known that I, LEE H. ADAMSON, a citizen of the United States, residing at Rogers, in the county of Benton and State 5 of Arkansas, have invented a new and useful Extensible Holder, of which the following is a specification.

The present invention appertains to an extensible holder, and is particularly an improvement over the cuff button or link disclosed in my Patent No. 1,101,049, issued June 23, 1914.

The present invention has for its object the provision of a novel and improved holding device of such construction and operation that a pair of terminal members may be normally pulled or drawn close together, and may be moved apart.

The device may be constructed as a cuff holder, as an eye glass or spectacle holder, and for kindred other purposes.

It is also within the scope of the invention to provide an extensible holder which is improved generally in its construction and details, to enhance the utility and efficiency thereof, the component parts being assembled in a unique manner to the desired ends.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed can be made within the scope of what is claimed without departing from the spirit of the invention.

The invention is illustrated in the accompanying drawing, wherein:

40 Figure 1 is a side elevation of the device constructed as a cuff holder. Fig. 2 is an enlarged sectional view of the cuff holder, one of the buttons or heads being detached from the shell or case, and being shown in full. Fig. 3 is a sectional view taken on the line 3—3 of Fig. 2, with the buttons both detached from the shell and illustrated in full. Fig. 4 is a sectional view taken on the line 4—4 of Fig. 2. Fig. 5 is a reduced 45 perspective view of the device as applied to a cuff and illustrating the cuff opened preparatory to rolling the same upward upon the sleeve. Fig. 6 is a perspective view 50 illustrating the device applied to a cuff with the cuff rolled up. Fig. 7 is an elevation of

the device utilized as an eye glass holder, portions of the cords being broken away.

Referring particularly to Figs. 1 to 6, inclusive, wherein the invention is embodied in a cuff holder, the cuff holder comprises a 60 central or intermediate shell or case 1, preferably constructed of sheet metal, and comprising a relatively large section 2, having a circular opening 3 at one side, and which is normally closed by the smaller section 4 of the shell. The shell is approximately 65 spherical in contour, although it may be of various formations. The section 2 is provided at diametrically opposite points with apertures 4' and beads 5 surrounding said 70 apertures, the apertures 4' being arranged adjacent the opening 3.

The margin or edge of the section 4 is secured upon the periphery or rim of a cup-shaped member 6 which fits snugly within 75 the opening 3 of the section 2 of the shell, to fasten the two sections of the shell together. The edge of the rim of the member 6 is provided with outturned lips or tongues 7 which are adapted to be passed through 80 recesses 8 provided in that edge of the section 2 defined by the opening 3 whereby the sections 2 and 4 may be assembled by moving the lips 7 through the recesses 8, and then turning the sections relative to one 85 another so that the lips 7 engage behind the respective edge of the section 2 for locking or latching the two sections of the shell together.

A central spindle 9 is mounted within the 90 shell 1, the same having rounded ends seated in central outstruck portions or seats 10 and 11 with which the respective sections 2 and 4 are provided. The spindle 9 is disposed between the apertures 4, and is arranged at 95 right angles to a line connecting the said apertures. A sleeve or hub 12 is mounted for rotation upon the spindle 9 between the member or partition 6 and the section 2, and an annular reel member or drum 13 is 100 mounted for rotation upon the sleeve 12. The reel member 13 is shorter than the sleeve 12, and a pair of rings 14 and 15 are secured upon the member 13 to provide the rim of the reel. The rings 14 and 15 are 105 provided at their remote edges with annular outturned flanges 16 and 17, and the flange 17 is provided with an annular flange 18.

A spiral spring 19 is disposed between the reel and the member 6, and has its outer end 110

secured to the rim of the member 6 and its inner end secured to sleeve 12, and a similar spring 20 is disposed within the flange 18 of the reel, and has its outer end attached 5 to the flange 18 and its inner end attached to the sleeve 12. The springs 19 and 20 extend in opposite directions whereby when one spring is wound up, the other will also be wound up, or in other words, whereby 10 the springs wind and unwind simultaneously.

Cords or flexible elements 21 pass through the apertures 4 and have their inner ends secured to the rings 14 and 15 whereby the 15 springs 19 and 20 in unwinding will normally wind the cords 21 upon the reel to bring the remote ends of the cords 21 adjacent the shell 1.

Buttons or heads 22 are attached to the 20 remote or outer ends of the cords 21, each of the buttons 22 comprising an outer curved plate 23, and a flat inner plate 24, the edge or margin of the plate 23 being beaded or bent over the edge of the plate 24, as at 25 25, in order to provide a hollow knob. The inner plate 24 is provided with an elongated slot 26, and with a depression or concaved seat 27 intermediate the ends of the slot 26. The outer plate 23 is provided with a de- 30 pression or concaved seat 28 opposite the depression or seat 27, and a ball or spherical member 29 is seated between and rotatable within the seats 27 and 28. A tubular shank 30 has one end secured within the ball 29 35 and projects through the slot 26, and a tubular member 31 is secured within the shank 30 and the cord 21 projects or passes through the member 31 and is provided with a knot 32 within the ball 29 for anchoring the re- 40 spective end of the respective cord 21 to the knob or button 22. The protruding end of the shank 30 is provided with longitudinal slots 33 whereby the protruding end of the shank may contract and expand, and said 45 end of the shank is provided with a bead 34.

In use, the buttons or knobs 22 are engaged outwardly through the button holes of the cuff C so that the shanks 30 of the button project inwardly through the button-holes, and the shell 1 will lie between the ends of the cuff, the parts being constructed of suitable size in order that the cuff holder will not be cumbersome. The buttons 22 are mounted for oscillation upon the shanks 30, since the balls 29 may oscillate or rotate 50 within the buttons 22, and the shanks 30 may oscillate within the slots 26, and in this manner the buttons 22 may be swung toward the axes of the shanks 30 so that 55 the buttons can be readily slipped outwardly through the button-holes, in applying the holder to the cuff. The protruding ends of the shanks 30 of the buttons are normally snapped through the apertures 4 within the 60 beads 5 of the shell 1, to attach the three 65

main parts of the holder, or to attach the buttons to the shell 1, so that the ends of the cuff will be held together properly. The buttons 22 being mounted for oscillation upon the shank 30 will also allow said buttons to swing relative to the shanks and shell for properly lying against the ends of the cuff. The present device is particularly useful for enabling the cuff to be rolled back upon the sleeve, without the necessity of detaching the holder or cuff button from the cuff, since the shanks 30 of the buttons 22 may be drawn out of engagement with the shell 1, and the buttons can be separated as indicated in Fig. 5, to allow 70 the cuff to be rolled or folded back upon the sleeve, as illustrated in Fig. 6. The cords 21 being separated with the buttons 22, will be unwound from the reel, and the reel will be rotated against the tension of the 75 spring 20, the spring 20 carrying the sleeve 12 therewith, and this will also serve to wind up the spring 19 with the spring 20. The springs 19 and 20 normally tend to retract the cords and wind the same upon the 80 reel, for moving the shanks 30 into engagement with the shell 1, although when the shanks 30 are disengaged from the shell 1, the buttons or terminal members may be readily separated for opening the cuff, in 85 putting on or taking off the shirt, or for enabling the cuff to be readily rolled or folded back. The protruding ends of the button shanks 30 are adapted to snap into and out of engagement with the shell 1, 90 as will be apparent from the foregoing, and the provision of the two springs 19 and 20 enables the reel to rotate twice as far as it could if only one spring were used. Thus, the range of the device is widened, since 95 the buttons or terminal members may be separated a considerable distance. When the buttons are released, the springs 19 and 20 will immediately come into play for 100 winding the cords 21 upon the reel to yieldably move the buttons toward one another and toward the shell 1.

The component parts of the device may be readily assembled, and the structure is such that the device may be made relatively small, 105 and at the same time, the parts may be separated to a considerable extent. The two springs will enable the device to be constructed lighter and smaller than if a single spring were employed.

Fig. 7 illustrates a different use of the device, for in this case, the device is constructed as an eye glass holder. Thus, the free end of one cord 21 is attached to an eye glass E, while the free end of the other cord 21 is attached to a pin or member P for attaching the said cord to the garment of the wearer. The device thus enables the cords 110 to be separated when the eye glass is worn, and when the eye glass is idle, the 115

5 cords 21 will be wound up within the shell 1 to suspend the eye glass close adjacent the pin P. In this form of the device, suitable pawls or other means are provided for holding the reel unwound against the tension of the springs, when the cords 21 are separated, said pawls or means being the same as are used in ordinary eye glass or spectacle holders.

10 Having thus described the invention, what is claimed as new is:

1. In a device of the character described, a shell, a rotary member mounted therein, a reel mounted for rotation upon the rotary member, a flexible element connected to the reel to be normally wound thereon, a spiral spring connecting the reel and rotary member, and a second spring connected to the rotary member and shell whereby the springs 20 act in unison to rotate the reel to wind the flexible elements thereon.

2. In a device of the character described, a shell, a spindle therein, a sleeve mounted for rotation upon the spindle, a reel mounted 25 for rotation upon the sleeve, a pair of flexible elements connected to the reel to be normally wound thereon, a spiral spring connecting the sleeve and reel, and a second spiral spring within the shell connected to 30 the sleeve and shell, both springs being

adapted to be wound up when the flexible elements are unwound from the reel.

3. In a device of the character described, a shell comprising a pair of sections, one having an opening and a pair of opposite 35 apertures adjacent said opening, a member detachably engaged within said opening, the other section of the shell being engaged to said member, a spindle within the shell between said apertures and extending through 40 said member, the sections of the shell having means receiving the ends of the spindle, a sleeve rotatable upon the spindle, a reel rotatable upon the sleeve, a pair of flexible elements extending through said apertures 45 and attached to the reel to be normally wound thereon, a spiral spring connecting said member and sleeve, and a spiral spring connecting the sleeve and reel, the springs being adapted to be wound up in unison 50 when the flexible elements are unwound from the reel.

In testimony that I claim the foregoing as my own, I have hereto affixed my signature in the presence of two witnesses.

LEE H. ADAMSON.
